US00D843245S

(12) **United States Design Patent** (10) **Patent No.:** **US D843,245 S**
(45) **Date of Patent:** **** Mar. 19, 2019**

(54) **WALL MOUNTABLE CONNECTOR**

(71) Applicant: **Ademco Inc.**, Golden Valley, MN (US)

(72) Inventors: **Travis Read**, Little Canada, MN (US);
David J. Emmons, Plymouth, MN (US);
Jonathan Erbacher, Minneapolis, MN (US)

(73) Assignee: **Ademco Inc.**, Golden Valley, MN (US)

(**) Term: **15 Years**

(21) Appl. No.: **29/611,100**

(22) Filed: **Jul. 18, 2017**

Related U.S. Application Data

(63) Continuation of application No. 29/554,637, filed on Feb. 12, 2016, now Pat. No. Des. 794,478.

(57) **CLAIM**

The ornamental design for a wall mountable connector, as shown and described.

DESCRIPTION

FIG. 1 is a perspective view of a wall mountable connector; FIG. 2 is a front side view of the wall mountable connector of FIG. 1;

FIG. 3 is a left side view of the wall mountable connector of FIG. 1;

FIG. 4 is a right side view of the wall mountable connector of FIG. 1;

FIG. 5 is a top side view of the wall mountable connector of FIG. 1; and,

FIG. 6 is a bottom side view of the wall mountable connector of FIG. 1.

The portions illustrated in broken lines on the figures are for illustrative purposes only and form no part of the claimed design.

1 Claim, 6 Drawing Sheets
